UNITED STATES PATENT OFFICE

HARLEY D. PENNINGTON, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA

THREADING DIE HOLDER

Application filed August 3, 1927. Serial No. 210,302.

This invention relates to threading die holders and is particularly useful for die holders employed in threading machines for large size pipe.

In machines for threading pipe of large diameter the dies are generally very heavy. They are usually carried by a pair of holder arms which are pivotally connected to the frame of the threading machine. Some provision must be made for separating the holder arms when it is desired to disengage the threading dies from a pipe. The construction heretofore employed has usually comprised a shaft having right and left hand threads thereon, these threads engaging nuts carried by the holder arms. Rotation of the shaft in one direction has been effective for bringing the dies together, and rotation thereof in the opposite direction has been effective for spreading them apart so as to free the pipe. This construction is undesirable because it requires considerable effort to move the heavy holder arms, is slow in operation, and is open to the objection that accurate setting of the dies is difficult.

I provide toggle means for moving the die holder arms. Preferably the holder arms are arranged so as to have crossed portions, and the toggle is connected to these portions. Guide means are provided for the toggle and the construction is such that the parts are in substantial balance and are easily operated. The toggle arms are preferably so arranged that they do not depend upon pivot pins for making their working engagement with the holder arms. On the contrary, they are arranged to make direct bearing engagement with the holder arm structures and thus it is insured that the parts will always be returned to their proper position, insuring accurate setting of the threading dies.

In the accompanying drawings, which illustrate certain present preferred embodiments of the invention,

Figure 1 is a front elevation of the threading die holders, and a portion of the frame of a threading machine having one form of the invention applied thereto,

Figure 2 is an end elevation of the apparatus shown in Figure 1,

Figure 3 is a section taken on the line III—III of Figure 1,

Figure 4 is a view corresponding to Figure 1, but showing another form of the invention.

Figures 1 to 3 show a frame member 2 of a threading machine having holder arms 3 and 4 pivotally connected thereto at 5. The holder arms 3 and 4 each carries threading dies indicated in chain lines at D.

The top holder arm 3 has a downwardly extending portion 6 terminating in a buttress 7. The lower holder member 4 is forked so as to accommodate the portion 6, the forked portions 8 extending upwardly and uniting to form a buttress 9.

Each buttress is recessed to receive the squared end of a pivot block 10 having a stem 11 extending to the outside of the buttress. Each stem is threaded to receive a holding nut 12, and a spring 13 is interposed between the nut and the buttress proper. A wedge 14 fits between the pivot block 10 and the buttress, the position of the wedge being determined by nuts 15 adjustable along studs 16. By adjusting the position of the nuts 15 the pivot blocks may be moved toward or away from one another.

The pivot blocks 10 are connected by arms 17 and 18 forming a toggle joint. The arms 17 and 18 are loosely coupled to the pivot blocks by pivot pins 19. These pivot pins are smaller than the openings provided therefor in the toggle links, as shown in Figure 3. This provides a direct bearing between the toggle links and the pivot blocks for holding the buttresses apart. It is when the buttresses are held apart that the threading dies are in working position. When the toggle is operated to draw the pivot blocks together, the dies are spread apart so as to release the pipe. At this time pivot pins 19 come into play.

When the toggle arms are in the straight line position of Figure 1, that is to say, so as to hold the threading die portions in their working position, the arm 17 makes a direct bearing connection with the arm 18. The arm 18 is provided with a bearing portion 20 for this purpose. The arms are loosely coupled by a pivot pin 21 extending through an enlarged opening in the arm 17 and through

- openings formed in the skirts 22 on the arm 18. The pivot pin 21 is elongated and passes through links 23 and slide blocks 24. The links 23 are connected to an operating lever 25 pivoted to the frame member 2 at 26. The slide blocks 24 work in guide slots 27. One of the guide slots is formed in the frame member 28. The frame member 28 is secured to bosses 29 formed on the frame member 2.
- Outside the frame members 2 and 28 the pivot pin 21 is provided with washers 30 held in place by cross pins 31. The washers 30 are shown in Figures 2 and 3, but are omitted from Figure 1 in the interest of clearness.
- When the lever 25 is in the solid line position of Figure 1, the threading dies are in their operative position. The toggle arms 17 and 18 lie in a substantially straight line and therefore form an unyielding brace for the die holder arms. The position of the arms is determined by the slide blocks 24 when they engage the ends of the slots 27. The dies may be adjusted by shifting the wedges 14 until the die members occupy the desired position.
- Thereafter the toggle may be operated as often as desired and the dies will always be returned to the same position.
- When the lever 25 is pulled down to the chain line position of Figure 1, the toggle arms occupy the position indicated in chain lines. This draws the buttresses 7 and 9 together and spreads the die members D apart. The opening movement just described is limited by the engagement of the slide blocks 24 with the ends of the slots 27.
- The die may be opened and closed very rapidly and is always moved to the same position on successive operations. By reason of the fact that the toggle arms are loosely coupled and directly engage the die holder structures, there is no chance of lost motion. The arms 3 and 4 substantially balance one another and the holder therefore operates smoothly.
- Figure 4 shows a different form of structure, wherein parts corresponding to similar parts in Figures 1 to 3 have been given the same reference character with an "a" suffixed thereto. In this form of the invention, the toggle arms 17a and 18a make direct bearing on the buttresses 7a and 9a. The buttresses are provided with ears 40 for holding pins 19a. These pins are loosely fitted so as to insure direct bearing of the toggle arms on the buttresses when the parts are moved to operative position.
- The toggle arms 17a and 18a are connected through a pin 41 to an arm 42. The arm 42 is connected through a pin 43 to an arm 44. The arms 42 and 44 constitute a second toggle. The arm 44 is rotatably mounted on a rock-shaft 45 carrying an operating lever 46. When the operating lever is in the position shown, the toggle arms 42 and 44 lie in substantially a straight line and hold the thread-

ing dies in their working position. When the operating lever 46 is moved downwardly, the buttresses 7a and 9a are drawn together so as to open the die.

The pin 41 is carried by a slide 47 working in a frame member 48. The rock shaft 45 is also carried in a slide 49. The slide 49 may be adjusted to different positions in the frame member 48 by means of a screw 50 having a locking nut 51. If it is desired to set the dies a little closer together, the block 49 is moved to the left, as viewed in Figure 4. This causes the toggle arms 17a and 18a to assume a more nearly straight line position upon closing of the die. If it is desired that the final setting of the die members shall be a little further apart, the screw 50 is operated to adjust the block 49 to the right. A stop 52 is provided in the frame 48. This stop bears against the arm 44 when it is in the working position. It cooperates with the arm regardless of the position of the block 49.

The construction shown in Figure 4 possesses all of the advantages of the form shown in Figures 1 to 3, and has the further advantage that the blocks and keys employed for adjusting the mechanism of Figures 1 to 3 is eliminated and a single adjusting means secured to the frame is substituted. In either case, the toggle arms, by reason of the loose pin connections, are so formed as to have a direct bearing on the die holder structures.

I have herein illustrated and described the present preferred forms of my invention, but it will be understood that the application is not thus limited, as it may be otherwise embodied within the scope of the following claims:

I claim:

1. A threading die holder comprising a frame, a pair of holder members carried by the frame, a toggle connecting the holder members, a pivot pin connecting the arms of the toggles, guide blocks on said pin and means engaging said blocks for guiding the pivot pin in the frame.

2. A threading die holder comprising a pair of holder members, the holder members being pivotally mounted and extending horizontally from such pivotal mounting, the holder members having crossed portions, a toggle connected to such portions, the toggle having a horizontally movable pivot and a support for the pivot.

3. The combination with die holders pivotally connected and having crossed opposing buttresses, of an extensible toggle mechanism comprising a pair of substantially straight pivoted toggle arms, pivot blocks at the ends of said arms for engagement with said buttresses, the mounting of said blocks and arms on their pivots being loose so that force may be transmitted directly therebetween without stressing the pivots, and means

for extending said arms to clamp said holders together.

4. A threading die holder comprising a pair of holder members which are pivoted at one extremity and have crossed buttress extensions at their opposite extremities, and toggle mechanism for opening and closing said members including a pair of extensible toggle arms which are pivoted at one extremity at a common operating point and at 10 their opposite extremities have a pivotal connection with relation to said buttress extensions, a clearance space being provided around each pivotal connection so that the bearing pressure is applied directly to said 15 arms instead of the pivots when the arms are extended to move the holder members to closed position.

5. A die holder comprising a pair of pivoted die-holding members formed with crossed extensions, and toggle mechanism for opening and closing said members comprising a pair of substantially straight extensible toggle arms which are pivotally connected at 20 one extremity at a common operating point and at their opposite extremities are pivotally connected to said extensions.

6. A die holder comprising a pair of pivoted die-holding members formed with crossed extensions, and toggle mechanism for opening and closing said members comprising a pair of substantially straight extensible toggle arms which are connected at 25 one extremity to a common pivotal connection and at their opposite extremities are provided with pivot blocks which engage said extensions, a guide block for said common pivotal connection, and lever means for operating said toggle mechanism.

40 In testimony whereof I have hereunto set my hand.

HARLEY D. PENNINGTON.
